MACHINE FOR APPLYING HEEL COVERS

Norwood H. Knowlton, Rockport, Mass., assignor
to United Shoe Machinery Corporation, Paterson, N. J., a Corporation of New Jersey

Application March 6, 1931. Serial No. 520,676

23 Claims. (Cl. 12—42)

This invention relates to machines for applying heel covers and is herein illustrated as embodied in a machine for bending over the edge of a heel and applying to the attaching face of the heel the 5 marginal portion of a cover which has previously been positioned and brought into contact with the lateral surface of the heel.

In covering heels for women's shoes such, for example, as the wood heels which are extensively 10 used, a coating of adhesive is applied to the heel cover or the heel, or both, after which the cover is applied to and drawn smoothly into contact with the lateral surface of the heel, namely, the side and rear faces thereof, the marginal portion of 15 the cover projecting beyond the upper edge of the heel, which is to be understood throughout the following specification and claims as designating the corner or edge defined by the junction of the lateral surface and the attaching face of 20 the heel regardless of its position. The next step is to bend and draw this projecting marginal portion of the heel cover over the edge of the heel and press it down firmly upon the attaching face.

The last-mentioned operation requires considerable 25 care to draw the cover smoothly over the heel edge, distribute the extra fullness evenly where the marginal portion of the cover is bent inward and press it down evenly and firmly upon the attaching face of the heel, and is a tedious 30 operation because of the long distance around the periphery of the attaching face.

It is an object of the present invention to provide a machine with the aid of which this operation 35 may be performed in a uniform, perfect manner almost instantaneously, whereby both the quality of the product may be improved and the output greatly increased as compared with the hand operation heretofore practised.

In accordance with the foregoing, a feature of 40 the invention consists in a heel cover applying machine in which are combined means for wiping the projecting marginal portion of a cover over the upper edge of a heel and for pressing the wiped over cover into contact with the attaching face of the heel, said means being constructed and arranged to act at a substantial angle to the 45 upper edge of the heel along the rear and side edges of the heel upon relative movement of the heel and said means.

Another feature of value and importance consists in the provision of means for so arranging the cover material as it is wiped over the edge of the heel that the surplus fullness of the material 50 shall be evenly distributed, so that the smoothest

possible surface will result when the material is pressed into adhesive contact with the heel.

In the illustrated embodiment of the invention these desirable ends are attained by the provision of wipers between which and the heel, to 60 the lateral surface of which the cover has been applied, relative movement may be effected in a manner to wipe the projecting margin of the cover over the edge of the heel substantially simultaneously around the entire curved portion 65 of its periphery; and a coiled wire spring the convolutions of which constitute corrugations arranged to gather the marginal portion of the cover and insure even distribution thereof while the wiping operation is continued and completed. 70 After the wiping operation has been finished the heel, with the inwardly turned marginal portion of the cover still in contact with the convolutions of the spring, may be pressed firmly against the spring to increase and complete the adhesive 75 attachment of the cover, the spring being preferably supported in a manner to permit sufficient yielding to accommodate any normal amount of irregularity in the work.

In a convenient form of the invention the cover 80 wiping and applying elements may be, and as illustrated in the foregoing drawings are, collectively horseshoe shaped and constructed for closing movement upon the work, being preferably operated by movement of the work into 85 their field of operation as, for example, by mechanism including an element engageable with and movable by the heel being operated upon.

The foregoing and other features and advantages of the invention will best be understood 90 and appreciated from reading the following detailed description of one good embodiment thereof in connection with the accompanying drawings, in which

Fig. 1 is a perspective view of the essential 95 operating parts of the machine;

Fig. 2 is a longitudinal section from front to rear showing the work in position for the beginning of the operation;

Fig. 3 is a view similar to Fig. 2, showing the 100 parts at the conclusion of the operation;

Fig. 4 is a view in cross section showing the parts at the conclusion of the operation;

Fig. 5 is a plan view of the machine; and 105

Fig. 6 is a view of the machine in side elevation.

Referring first to Figs. 1 and 6, it will be seen that the machine is adapted to be mounted upon an upright column 10 which may be supported 110

in any suitable manner, as by a foot 12 in which it is shown as secured by a set screw 14.

The machine itself comprises a U-shaped base member 16 in which is secured by set screws 18 a horizontal bar 20 upon which is mounted a forwardly extending bracket 22 secured to the bar 20 by set screws 24.

Fastened to, and supported by, the bracket 22 by a screw 26 is a table 28 in the front end of which is a tapped hole for the reception of a screw 30 which passes through a slot 32 in an angular member having an upright arm 34 and a horizontal arm 36, the latter in connection with the upper end of the arm 34 constituting a T-shaped heel support upon which a heel may be placed with its attaching face down. The screw and slot mounting 30, 32 provides for vertical adjustment of the said heel support relative to the table 28.

The rear portion of the table 28 is extended at both sides of the machine, as best shown in Fig. 5, and near the extremities of the extensions vertical pins 38 are secured therein by set screws 40, said pins constituting stationary pivots about which relatively movable arms 42, converging toward the heel support 36, are adapted to swing. Attached to the inner ends of the arms 42 are wiper members 44 of substantially U-shaped cross-section, as shown in Figs. 2, 3 and 4.

The inner wall 46 of each of the wiper members has an inclined face 48, the function of which will presently appear, and the outer wall 50 is somewhat higher than the inner wall, for a reason which will also be explained herein-after.

A piece 52 of yielding material, such as soft rubber, is disposed in the bottom of the channel between the inner and outer walls 46, 50 of the wiper members, extending all the way around from the front end of one of said members to the front end of the other. A coiled wire spring 54 is also arranged in said channel, resting upon and being supported by the yielding element 52 and extending the full length of the channel 45 behind the inclined faces 48, retaining plates 56 preventing displacement of the spring 54 and the supporting element 52.

Both the spring 54 and the supporting element 52 are naturally straight, but are bent into approximately horseshoe shape and inserted in the channel, where they are retained under tension. Their resilience tends to cause them to straighten out and this tendency, supplemented, if necessary, by an auxiliary spring 58, see Figs. 55 2, 3 and 4, causes the wiper members to be swung forward about their pivots 38 and separated, as shown in Fig. 5, except when they are forcibly moved in the reverse direction, the said wiper members resting and sliding freely upon the upper surface of the table 28. It will be seen in Figs. 2, 3 and 4 that the upper, work engaging face of the coiled spring 54 rises above the upper edge of the wall 46 and lies below the upper edge of the wall 50.

For the purpose of closing the wiper members inward toward the heel support 36 there are provided links 60, the front ends of which are pivoted at 62 to the respective wiper members and the rear ends of which are pivoted at 64 to a lever 66 which is fulcrumed at 68 in a bracket 70 bolted to the base member 16. The connection between the bracket 70 and the base 16 is tongued and grooved as shown at 72, see Fig. 1, and when the securing bolt 74, Fig. 6, is loosened the bracket may be adjusted in position forward or rearward of its

support. In addition to this adjustment extra holes 76 are provided in the lever 66 and the bracket 70 in order that the vertical position of the fulcrum pin 68 may be varied as required. A similar series of holes 78 is provided in the upper end of the lever 66 and in any one of these may be inserted a pin 80 constituting a pivotal connection between the lever 66 and the rear ends of a pair of links 82 through the front ends of which passes a transversely arranged rod 84 having its ends secured by set screws 86 in the upper ends of a pair of rocker arms 88 which are in turn secured to a rock shaft 90 journaled in bearings 92 extending downward from the laterally extended rear portion of the table 28. Journaled upon the rod 84, between the links 82, is a roll 94 which constitutes an abutment arranged to be engaged by the back of a heel and thereby moved rearward to swing the lever 66 rearward about its fulcrum 68 and, through the links 60, to swing the arms 42 about their pivots 38 and close the wipers under the heel.

A stop screw 96 is threaded through the lever 66 and engages an abutment 98 formed on the rear edge of the table 28, thus adjustably limiting the forward position to which the lever 66 can move. A lock nut 100 secures the screw 96 in adjusted position.

The operation of the above-described mechanism will now be explained. Assuming a cemented cover 102 to have been applied to the lateral surface of a heel 104, either by hand or by machine, the heel is placed, attaching face downward, upon the heel support 36, as illustrated in Fig. 2, the back of the heel engaging the abutment roll or member 94. The heel is now pushed straight backward, moving the roll 94 and its connected mechanism and causing the wipers 44 to be moved inward and rearward about the pivots 38.

The marginal portion 106, Fig. 2, of the heel cover is first engaged by the inclined faces 48 of the inner walls of the wipers and bent around the edge of the heel toward its attaching face. As the relative movement of the heel and wipers continues the bent-in margin of the cover engages and rides upon the upper face of the coiled spring 54, the convolutions of which tend to gather and guide the surplus material into evenly distributed pucks and, it being understood that some downward pressure is being applied to the heel, to press the cover material thus arranged into contact with the attaching face of the heel. This relative movement is continued until the heel is engaged around its periphery by the outer walls 50 of the wipers which walls are made sufficiently high for this purpose, and sufficient pressure is applied to press the cover evenly and smoothly into contact with the heel around its edge. At this time the position of the work and the elements of the machine is as shown in Figs. 3 and 4. Extra downward pressure may now be applied to the heel, if desired, in order to press the wiped-over margin of the cover into firm contact with the attaching face of the heel and to produce a smooth, even surface. The heel is now ready for removal from the machine, the parts of which return to the position shown in Fig. 1, ready for the reception of the next heel to be operated upon.

Although the roll 94 moves in an arc about a fixed center 90 and the extent of its movement is determined in part by the profile of the back of the heel, the provisions for adjustment of the bracket 70, the fulcrum pin 68, the stop screw 96, and the pivot pin 80 make it possible to control the relative movement between the heel and the

- wipers to meet the requirements of heels of a large variety of sizes and shapes.
- Having described the invention, what I claim as new and desire to secure by Letters Patent is:
- 5 1. In a machine for applying heel covers, the combination of means for wiping a projecting marginal portion of a cover over the upper edge of a heel, and means for pressing the wiped over cover into contact with the attaching face of 10 the heel, said means being constructed and arranged to act at a substantial angle to the upper edge of the heel along the rear and side edges of the heel upon relative movement of the heel and said means.
- 15 2. In a machine for applying heel covers, the combination of means for wiping a projecting marginal portion of a cover over the upper edge of a heel, and means acting in the general plane of and at substantially right angles to the upper 20 edge along the sides and the rear marginal portion of the attaching face of the heel to distribute evenly the surplus of wiped over material upon said marginal portion of the attaching face.
3. In a machine for applying heel covers, the 25 combination of means for wiping a projecting marginal portion of a cover over the upper edge of a heel, and means for distributing evenly the surplus of wiped over material and pressing said material into contact with the attaching face of 30 the heel, said means acting in the general plane of and at substantially right angles to the upper edge of the heel along the rear and the sides of the marginal portion of the attaching face of the heel, and being constructed and arranged to 35 engage substantially simultaneously the marginal portion of the cover around the entire curved portion of the periphery of the attaching face of the heel to lay the same upon the attaching face.
4. In a machine for operating upon a heel 40 having a cover applied to its lateral surface with a marginal portion of the cover projecting beyond the upper edge of the heel, means acting radially of the attaching face of the heel for wiping in said marginal portion of the cover substantially simultaneously around the entire curved portion of the periphery of said attaching face.
5. In a machine for applying heel covers, the 45 combination of a heel support arranged to position a heel having a cover applied to its lateral surface with a marginal portion of the cover projecting beyond the upper edge of the heel, and a cover wiping and distributing element having cover engaging corrugations disposed radially of the attaching face of a heel positioned by said support.
6. In a machine for applying heel covers, a 50 cover engaging wiping and distributing member comprising a coiled wire.
- 60 7. In a machine for applying heel covers, a cover engaging wiping and distributing member comprising a coiled wire and a yielding support therefor.
- 65 8. In a machine for applying heel covers, a wiper having an inclined face constructed and arranged to engage and wipe a cover over an edge of a heel, and a coiled wire distributing and wiping element having a cover engaging face behind said inclined face.
- 70 9. In a machine for applying heel covers, a wiper having an inclined face constructed and arranged to engage and wipe a cover over an edge of a heel, and a coiled wire distributing and wiping element having a cover engaging face behind and rising above said inclined face.
10. In a machine for applying heel covers, a channel shaped wiper having an inclined cover wiping face upon one wall of the channel and a coiled spring in the channel, a cover engaging face of said spring extending beyond said wall. 80
11. In a machine for applying heel covers, a channel shaped wiper having an inner wall provided with an inclined cover engaging face, a coiled spring in the channel, said spring having a cover engaging face rising above said inner wall, and an outer wall extending above the cover engaging face of said coiled spring. 85
12. In a machine for applying heel covers, the combination of a pair of channel shaped pivoted wipers, and a coiled spring arranged in the channel, said spring being under tension and tending to move said wipers apart. 90
13. In a machine for applying heel covers, the combination of contractible, horseshoe shaped wiping means and mechanism operable by engagement of a heel therewith for contracting said wiping means to wipe a cover over an edge of the heel. 95
14. In a machine for applying heel covers, the combination of a plurality of cover wiping and applying elements which are collectively horseshoe shaped, constructed and arranged for closing movement relative to a heel, and mechanism including an element engageable with and movable by the heel for effecting said closing movement of the wiping and applying elements. 100
15. In a machine for applying heel covers the combination of a heel support constructed and arranged to sustain a heel with its attaching face down, wipers movable toward a heel upon said support and into wiping engagement with a downwardly projecting marginal portion of a cover upon said heel, a movable abutment normally disposed above the heel support in a position to be engaged by the back of the heel, and connections 110 between said abutment and the wipers for causing operative movement of the wipers when the abutment is moved backward by rearward movement of the heel. 115
16. A cover applying machine having, in combination, a horseshoe-shaped member comprising sections mounted for movement toward and away from each other, a support positioned between said sections and constructed and arranged to engage the attaching face of a heel 120 beyond the rim of which a marginal portion of a cover applied to the lateral face of the heel extends, and mechanism to move the sections of the horseshoe-shaped member toward each other to turn the marginal portion of the cover which 125 extends beyond the rim of the attaching face of the heel around said rim and to lay the said marginal portion upon the attaching face of the heel. 130
17. A cover applying machine having, in combination, a horseshoe-shaped member comprising sections mounted for movement toward and away from each other, a support positioned between said sections and constructed and arranged to engage the attaching face of a heel beyond the rim of which a marginal portion of a cover applied to the lateral face of the heel extends, an abutment member arranged for engagement with the heel, and mechanism controlled by the abutment member constructed and arranged to move the sections of the horseshoe-shaped member toward each other under pressure of the heel to turn the marginal portion of the cover extending beyond said rim around the same and to lay the cover upon the attaching face of the heel. 140
18. In a machine for applying heel covers, a 150

wiper having an inclined face constructed and arranged to wipe a cover over an edge of a heel, and a resilient distributing and wiping element having a cover engaging face positioned behind and extending beyond said inclined face.

19. A machine for applying heel covers having, in combination, a horseshoe-shaped member comprising sections mounted for relative movement, each of said sections comprising a wiper having a face inclined to the path of relative movement of said sections and constructed and arranged to wipe a marginal portion of a cover attached to a heel and extending beyond the rim of the attaching face of the same over said rim, and resilient means positioned behind and extending beyond the face of each of the sections and constructed and arranged to lay the marginal portion of the cover upon the attaching face of the heel.
20. In a machine for applying heel covers, the combination of substantially rigid means to wipe a projecting marginal portion of a cover over the rim of the attaching face of a heel, and resilient means to press the wiped-over marginal portion into contact with the attaching face of the heel.
21. A machine for applying heel covers having, in combination, a horseshoe-shaped wiper comprising a plurality of wiper sections, means to guide a heel beyond the rim of the attaching face 30 of which a marginal portion of a cover extends

against the sharply curved portion of the horseshoe-shaped wiper to inturn the marginal portion of the cover upon the rear marginal portion of the attaching face of the heel, and mechanism controlled by the heel to move the wiper sections together to cause the same to inturn the marginal portion of the cover upon the sides of the attaching face as the rear portion of the attaching face is being covered.

22. In a heel-covering machine, a horseshoe-shaped wiper formed by a pair of sections mounted for swinging movement about substantially parallel axes, respectively, included in a plane lying outside the horseshoe-shaped wiper and positioned adjacent to the sharply curved portion of the wiper.

23. In a heel-covering machine, a horseshoe-shaped wiper formed by a pair of sections mounted for swinging movement about substantially parallel axes, respectively, included in a plane lying outside the horseshoe-shaped wiper and positioned adjacent to the sharply curved portion of the wiper, and means operated by a heel having the marginal portion of its applied cover projecting above the rim of the attaching face to swing the sections toward said plane thereby to cause said sections to move toward each other and to inturn the projecting marginal portion upon the attaching face.
